(57) **CLAIM**

The ornamental design for an air freshening device, as shown and described.

DESCRIPTION

FIG. 1 is a perspective view of a first embodiment of an air freshening devices having an opaque dome and the back element in a downward position.

FIG. 2 is a front view of the air freshening device of FIG. 1.

FIG. 3 is a left side view of the air freshening device of FIG. 1.

FIG. 4 is a right side view of the air freshening device of FIG. 1.

FIG. 5 is a back view of the air freshening device of FIG. 1.

FIG. 6 is a top view of the air freshening device of FIG. 1.
FIG. 7 is a bottom view of the air freshening device of FIG. 1.
FIG. 8 is a perspective view of the first embodiment of the air freshening device having an opaque dome and the back element in an upward position.

FIG. 9 is a front view of the air freshening device of FIG. 8.
FIG. 10 is a left side view of the air freshening device of FIG. 8.

FIG. 11 is a right side view of the air freshening device of FIG. 8.

FIG. 12 is a back view of the air freshening device of FIG. 8.

FIG. 13 is a top view of the air freshening device of FIG. 8.

FIG. 14 is a bottom view of the air freshening device of FIG. 8.

FIG. 15 is a perspective view of a second embodiment of the air freshening device having a translucent dome and the back element in a downward position.

FIG. 16 is a front view of the air freshening device of FIG. 15.
FIG. 17 is a left side view of the air freshening device of FIG. 15.

FIG. 18 is a right side view of the air freshening device of FIG. 15.

FIG. 19 is a back view of the air freshening device of FIG. 15.

FIG. 20 is a top view of the air freshening device of FIG. 15; and,

FIG. 21 is a bottom view of the air freshening device of FIG. 15.

The broken line showing of environmental structure in FIGS. 1–4, FIG. 6, FIGS. 8–11, FIG. 13, FIGS. 15–18 and FIG. 20 is for illustrative purposes only and form no part of the claimed design.
